UNITED STATES PATENT OFFICE.

GEORGE E. SHERMAN, OF CHICAGO, ILLINOIS.

PORTABLE CLOSET.

1,137,431.

Specification of Letters Patent. Patented Apr. 27, 1915.

Application filed April 14, 1913. Serial No. 760,905.

To all whom it may concern:

Be it known that I, GEORGE E. SHERMAN, a citizen of the United States, residing in Chicago, county of Cook, and State of Illinois, have invented certain new and useful Improvements in Portable Closets, of which the following is a specification.

My invention relates to portable closets and has for its primary object the provision 10 of an improved collapsible device of this class.

With the above and other objects in view this invention consists substantially in the combination, arrangement, and construction 15 of parts all as hereinafter described, shown in the accompanying drawings which form a part of this specification and show the preferred embodiment of my invention, and more specifically set forth in the subjoined 20 claims.

In the drawings: Figure 1 is a perspective view of my invention, showing it hanging to the wall of a room and in position for use. Fig. 2 is a perspective view of the bottom 25 of the interior of my invention, the upper part being broken away. Fig. 3 is a view in perspective of the frame of my invention and showing clothes hangers attached thereto. Fig. 4 is a vertical section of a portion 30 of my invention taken approximately on the line 4—4 of Fig. 1, and looking in the direction indicated by the arrows. Fig. 5 is a vertical section of the upper frame of my invention on the line 5—5 of Fig. 3, looking 35 in the direction indicated by the arrows, but showing a different position of the parts of the upper frame than that illustrated in Fig. 3.

Reference numeral 10 indicates the wall of 40 a room, the floor of which is 11.

12 is an envelop of cloth or similar flexible material, preferably of a rectangular form and held in its desired shape by means of an upper frame indicated generally by A, 45 and by a bottom frame indicated generally by B.

The upper frame A comprises a rectangular strip 13 of metal or other suitable material, provided with a cross piece 14 of 50 similar material. Bails 15, preferably formed of strips of metal, are pivoted at one of their ends to the rear side of the strip 13 and at their forward ends to the cross piece 14, the pivots being formed 55 preferably of bolts 16 provided with retaining nuts 17. The bails are preferably angled

as shown most clearly in Figs. 1, 3, and 4, and they are pierced as at 18 and slotted as at 19 for engagement with cap-screws 20 or other supporting members protruding 60 from the wall 10. A supporting rod 21 for clothes hangers 22 or other objects is preferably provided with offset ends 23, pivoted to opposite sides of the frame 13. From this description it will be seen that the bails 15 65 and the rod 21 may be folded down substantially into the plane of the strip 13, thereby conserving space required in packing the frame for transportation. The top of the envelop 12 is provided with slits 24 70 to accommodate the portion of the bails 15 which protrude without the envelop.

The bottom frame is formed preferably of a single strip of metal 25 similar to the strip 13 and which is preferably adapted to 75 rest within the bottom of the envelop 12 without being secured thereto, though if desired fastenings may be provided between it and the envelop.

Access is had to the interior of the closet 80 through any desired form of opening, preferably that shown at C in Figs. 1 and 2, wherein two edges of the envelop 12 overlap in a vertical line disposed in the center of the forward side of the envelop. The overlapping edges of the envelop are closed by suitable fastening devices such as the well known spring and socket snaps 26, forming a dust-proof closet within the envelop.

My invention is well adapted to be carried from place to place and in addition to this portable feature is collapsible into an extremely small packing space. The walls of the envelop 12 may be readily folded between the top and bottom, and the various 95 supporting devices described are foldable substantially into the plane of the top. The envelop 12 is readily removed and being preferably formed of a washable cloth is easily cleaned.

In the accompanying drawings and in the foregoing description is set forth the preferred embodiment of my invention, but it is obvious that one skilled in the art may make modifications thereof without departing 105 from its spirit.

I claim:

1. The combination of an envelop of flexible material, a hollow frame attached to the upper end thereof and distending the envelop to form a dust proof chamber, fastening devices upon the frame for attachment

to supports, and a hanger rod supported by the frame, said fastening devices and hanger rod being collapsible into the frame substantially into the plane of the latter.

- 5 2. The combination of a frame having its central portion open, an envelop of flexible material secured to the outer edge of the frame, fastening members pivoted to said frame and adapted to swing into the opening of the frame to a position substantially 10 coplaner with the latter, and a hanger rod

pivoted to said frame and adapted to swing into the opening of the frame against said fasteners.

In testimony whereof I have signed my 15 name to this specification, in the presence of two subscribing witnesses, on this 11th day of April, A. D. 1913.

GEORGE E. SHERMAN.
